UNITED STATES PATENT OFFICE.

ELIJAH LAMB, OF CAMDEN, NEW JERSEY.

ELASTIC WEBBING.

SPECIFICATION forming part of Letters Patent No. 410,839, dated September 10, 1889.

Application filed September 5, 1887. Serial No. 248,854. (Specimens.)

To all whom it may concern:

Be it known that I, ELIJAH LAMB, a citizen of the United States, and a resident of Camden, Camden county, New Jersey, have 5 invented certain Improvements in Elastic Webbing, of which the following is a specification.

The object of my invention is to prevent the puckering of the edges of a strip of elastic 10 webbing and to cheapen and simplify the manufacture thereof, and at the same time impart an ornamental finish to the edges of said strip, as fully described hereinafter.

In the accompanying drawings, Figure 1 is 15 a perspective view of a strip of elastic webbing made in accordance with my invention. Fig. 2 is a diagram illustrating the method of weaving adopted in carrying out my invention. Fig. 3 is an enlarged view illustrating more clearly the disposal of the threads; 20 and Fig. 4 is a transverse section on the line 1 2, Fig. 3.

Narrow strips of elastic webbing are now 25 produced upon what are termed "swivel" or "gang" looms, employing a special shuttle-race and shuttle for each strip of fabric to be woven. This necessitates the use of a very wide loom, if a large number of strips are to be woven thereon, and close and constant 30 attention is demanded on account of the number of independent shuttles which are used, each shuttle being necessarily small and of limited yarn-carrying capacity. The formation of the usual selvages on the 35 elastic webbing is objectionable, because the weft-threads as they are thrown across the shed bear upon and cut into the outer strands of rubber and thus detract from the elasticity of the same and cause puckering of the edges 40 of the strip, and when this elastic webbing is used a constant rubbing of the weft-threads against the outer strands of rubber cuts them in small sections, often rendering the first and second strands useless.

45 In carrying out my invention I use an ordinary loom, and I arrange the warp-threads with the elastic strands *g* in sets *a*, with intervening spaces *b*, the outer sets of warps *a* being few in number, as they serve simply as 50 selvaging-warps and are independent of the woven strips. The weft-threads *d* are introduced by picking the shuttle from side to

side of the loom, as usual, so as to produce a series of woven strips located side by side, with intervening spaces across which the 55 weft-threads extend from strip to strip, and from the outer strips to the selvaging-warps. Thus the outer strands of rubber *g* are not injured by the returning of the weft-threads, and are consequently in perfect condition 60 when they leave the loom, and all puckering and wrinkling of the edges of the strip being effectually prevented, as this puckering is caused by the breaking of the strands of rubber. After the weaving the fabric is sev- 65 ered on the line *x x*, so as to separate the strips and form on the opposite edges of the strip a fringe, due to the projecting weft-threads, thus imparting an ornamental finish to each edge of the strip, the fringe being, if 70 desired, cut to form ornamental patterns.

In order to prevent the raveling out of the warp-threads at the edges of the strips, a number of warps at and near each edge of the strip are tied or bound together and to 75 the wefts by means of a doup-thread *f*, as shown in Fig. 3.

It will be understood that the elastic webbing, when in use, has a constant strain upon it—as in suspenders, or in elastic garters, for 80 instance—so that it will be seen that it is desirable to have an article in which the strands of rubber are all intact.

I claim as my invention—

1. A strip of elastic webbing having a body 85 composed of warp-threads and disconnected weft-threads, longitudinal elastic strands embedded in the fabric, and doup-threads tying the edge warps to the weft-threads, substantially as described.

2. A strip of elastic webbing having a body composed of interwoven warps and wefts, elastic strands embedded therein, doup-threads tying the edge warps of the strips, 95 and fringed edges formed by projecting ends of the wefts, all substantially as described.

In testimony whereof I have signed my name to this specification in the presence of two subscribing witnesses.

ELIJAH LAMB.
